UNITED STATES PATENT OFFICE.

WILLIAM T. GREEN, OF COVINGTON, KENTUCKY.

PLUG-TOBACCO PRESS.

SPECIFICATION forming part of Letters Patent No. 276,680, dated May 1, 1883.

Application filed March 11, 1882. (No model.)

To all whom it may concern:

Be it known that I, WILLIAM T. GREEN, a citizen of the United States, residing at Covington, in the county of Kenton and the State of Kentucky, have invented a new and useful 5 Tobacco-Press, of which the following is a specification.

My invention relates to a tobacco-press that will press tobacco by lever-pressure to exact 10 size and weight, ready for the finishing-press without loss by chipping away or adding to this pressed plug before finished.

The mechanism of my improved tobacco-press is illustrated in the accompanying drawings, in which—

Figure 1 is a plan on line 3 and 4 of Fig. 2; Fig. 2, a front elevation. Fig. 3 is a section of press C on line 1 and 2 of Fig. 1, turned on its side; Fig. 4, a section of press B on line 1 and 20 2 of Fig. 1; Fig. 5, a section of press C on line 5 and 6 of Figs. 1 and 2; Fig. 6, a section of press B on line 7 and 8 of Figs. 1 and 2; Fig. 7, a plan of clamp X, to hold smoking-tobacco funnel in press C; Fig. 8, an end view of said 25 clamp X; Fig. 9, a view of the clamp fixed, with the plunger-block G' and mold F taken out of press C, on line 5 and 6 of Figs. 1 and 2.

Similar letters refer to similar parts throughout the several views.

30 A is the table, on which the tobacco is weighed and molds are filled; a, screws passing through the cramp P and into the top follower D, for adjusting said follower, so as to have the plug to any thickness required; B, presser-35 press producing an upward pressure by means of a double lever, J J, extending both sides of the press, so that two persons could press upon them; b, screws passing through top follower D to fasten the presser-block G; b', screws 40 passing through top follower D' of press C to fasten plunger-block G'. Any size of presser-blocks or plunger-blocks can be fixed to the followers D and D' of press B and press C, and adjusted to suit the thickness of the plug 45 needed by the adjustable follower D. C is the plunger-press, producing a downward pressure by means of the lever L; D, top follower of press B, working between and guided by the posts f; D', top follower of plunger-press C, 50 guided by posts f; d, iron rods that fasten the top follower D' to the ledge H. These rods work loose in bottom T. E is the bottom follower of press B, upon which the molds F stand and the tobacco pressed; e, bottom post or legs of the press; F, molds made of any 55 size; f, top frame-work or posts of the two presses B and C; G, presser-block made to fit the molds, convexed on the bottom. This convexity is for the purpose of pressing more tobacco to the edges, so that when it is put in 60 the finishing-press the plug produced will have sharper and fuller edges as a finished plug. G' is the plunger-block, made to fit the molds, having straight bottom, and used in press C to press the tobacco out of the molds into the 65 box S; g, joint where the two levers J J meet, and are fixed to piston K in press B, the holes in both levers being oblong; H, a stiff ledge, to which the follower D' is attached by means of the bolts or rods d, and by means of the 70 adjustable connection M it is attached to the lever L in press C; h, fulcrum of levers J J in press B; K, piston connecting the levers J J and the bottom follower E; L, lever of press C; M, connecting-rod between lever L and 75 ledge H; m m, two prongs of the clamp X, used to hold the funnel u when smoking-tobacco is put up in the press C. These prongs are adjustable by the screw p, and the joint q is tightened by the screw w. N are two 80 circular pieces of flat iron turned edgewise, made so as to give the levers J J a fulcrum in holes punched in them at h; P, iron cramp, fastened to posts f of the press B, through which the screws a are made to work, so as to adjust the follower D; p, screws to adjust the prongs m m of the clamp X; q, joint of the prongs m m, like the joints of a pair of shears; R, lever connected to levers J J by means of the rope r for the purpose of relieving any 85 tendency of the follower E to stick, caused by tobacco juice. r is a rope connecting levers J J and R; S, box, into which the pressed tobacco falls when the molds are discharged by the plunger-block G'; T, bottom of the box S, 90 into which the posts f are mortised; u, funnel through which smoking-tobacco is filled and pressed in the sack Y in press C; V, pin that passes through the clamp X and posts f, to fasten and be a fulcrum for said clamp; W, 95 100

weight used to lift and bring back the plunger-press C after having pressed the tobacco out of the molds into box S; w, pin that fastens the prongs m m of the clamp X at their joints; 5 X, clamp used for holding the funnel u in putting up smoking-tobacco in press C. This clamp is fixed to posts f by pin V, and is taken away when smoking-tobacco is not put up. Y is the sack for smoking-tobacco, fixed around the 10 funnel u to be filled and pressed; Z, smoking-tobacco plunger, fixed in follower D' of press C, which is of course detachable, and fastened by a pin or in any other way.

This machine is built of hard wood and iron, 15 as shown.

The operation of this press is as follows: The table A holds on it the tobacco and a pair of scales with which the tobacco to be pressed is weighed, and then carefully spread in the 20 mold F, as even as possible. The mold is then pushed on the follower E of the press B, with the presser-block G in position. The levers J J are then pressed, producing an upward pressure or carrying the molds up and against 25 the pressure-block G, and the tobacco is pressed to the desired thickness. When pressed the mold is pushed onto the press C, with its plunger-block G' in position, and the tobacco is pressed out of the molds by the downward 30 pressure of the plunger-block G', caused by pressing the lever L, and the tobacco falls into the box S, and is then ready for the wrapper and finishing-press without adding to or chipping away any tobacco. It should be here 35 stated that the presser-block G and the plunger-block G' fit loose in the molds. Hence there is no difficulty about the withdrawing of the molds from each press.

The clamp X is only used for smoking-to-

bacco (in the press C when the plunger-block 40 G' and mold F is not attached) with the plunger Z in the adjustable follower D'. With the movement given this clamp by the fulcrum V, any size of sacks can be filled and pressed. This clamp X is dependent upon the press C. 45 Hence both mutually contribute to produce the new result.

What I claim is—

1. The combination of a tobacco-press having an adjustable follower, D, adjusted by 50 screws a a, passing through cramp P, acting as a fulcrum, and having an adjustable and detachable presser-block, G, adjusted by screws b b, passing through said follower D, acting as a fulcrum, against which presser-block G in 55 the machine an upward pressure by lever-power presses the tobacco to the required thickness, substantially as shown and described.

2. The combination of a tobacco-press and an adjustable follower, D', adjusted below by 60 screw M, the said follower D' having screws b' b', passing through it to adjust the detachable plunger-block G', said plunger-block having a perpendicular thrust to force the tobacco out of the molds, substantially as shown and 65 described.

3. In a tobacco press, the presser-blocks made convex on their faces to press the tobacco more in the center, thereby pressing more tobacco to the edges, so that the finishing-press will give a sharper and better edge 70 to the plug, substantially as shown and described.

WILLIAM T. GREEN.
